COMBINED STORAGE TANK AND DISPENSING UNIT FOR LIQUIFIED PETROLEUM GAS

Thelmer A. Rogers, Lubbock, Tex.

Application December 12, 1955, Serial No. 39,280

Term of patent 3½ years

(Cl. D91—1)

Fig. 1 a front elevational view of a combined storage tank and dispensing unit, showing my new design;

Fig. 2 a top plan view;

Fig. 3 a side elevational view; and

Fig. 4 a side elevational view taken from the side opposite Fig. 3.

I claim:

The ornamental design for a combined storage tank and dispensing unit for liquified petroleum gas, as shown.
